UNITED STATES PATENT OFFICE.

JASPER A. McCASKELL, OF SALT LAKE CITY, UTAH.

MINE-CAR LUBRICATION.

1,105,363.

Specification of Letters Patent. Patented July 28, 1914.

Application filed August 9, 1912. Serial No. 714,187.

To all whom it may concern:

Be it known that I, JASPER A. McCASKELL, a citizen of the United States, residing at Salt Lake City, in the county of Salt Lake and State of Utah, have invented certain new and useful Improvements in Mine-Car Lubrication, of which the following is a specification.

This invention relates especially to mine-car-lubrication, and it consists of the improved lubricating mine-car wheel which I will hereinafter fully describe and claim.

In the accompanying drawings forming part of this specification and in which similar reference characters indicate like parts in the several views, Figure 1 is a vertical section of a mine-car wheel embodying my invention. Fig. 2 is an elevation of the same. Fig. 3 is a sectional view of the exterior cap removed. Fig. 4 is an elevation of the cap of Fig. 3. Fig. 5 is an enlarged vertical section of the hub-portion of the wheel showing a means for subjecting the lubricating oil to pressure.

In carrying out my invention, I take a mine-car or other wheel, A, of any suitable construction, size and design and form the same with an enlarged chamber, B, which surrounds the central opening, A', and which opening is counterbored to receive a bushing, C, said bushing having perforations, a, made radially through it and communicating with the enlarged lubricant-containing chamber, B, whereby oil or other lubricating material may be constantly fed to the axle, upon which the wheel turns.

The axle, D, is of any well known construction and has its journal end, d, fitting the bushing, C, and projecting beyond the outer side of the wheel and adapted to receive a split key or cotter-pin, E, or equivalent device by which the axle may be locked to a washer, F, and the wheel thereby retained in place on the journal-end of the axle.

At the inner end of the bushing is arranged a suitable cup washer, G, which fits snugly around the shaft and has its open side presented toward the annular lubricant-containing chamber, B, said washer adapted to prevent the escape of oil in that direction.

The annular chamber which surrounds the bushing, C, may be of any suitable dimensions, and leading from this chamber outwardly through the outer side of the hub

of the wheel is a pipe, H, to which is fitted a stop-cock, I, of some appropriate type and which is adapted to be closed after oil has been forced through said pipe into the chamber, B, surrounding the bushing. The pipe is designed to be connected to some suitable source of pressure supply and to this end compressed air may be utilized so that when the oil or other lubricating material is admitted to the chamber it is under considerable pressure and the air in this chamber will be forced to the upper portion thereof. The stop-cock, I, is now closed and the contained air in the chamber is held under pressure and the pressure of this air is employed for forcibly feeding oil through the perforations in the bushing and to the journal portion of the axle, thereby automatically lubricating the latter.

The outer end of the hub-portions of the wheel is provided with annular flanges, J, which are undercut as shown at j, and are separated from each other to form spaces, K, to admit corresponding lugs, or flanges, L, projecting from the circumference of a suitable cap, M, of segmental form in cross-section adapted to fit over and form a closure for the outer end of the bushing and end of the axle, said lugs, L, and the walls of the undercut portion of the flanges, J, being preferably cam-shaped so that when the cap is given a partial rotation after its lugs have been entered into the spaces, K, between the oppositely placed flanges or lugs, L, the cam-surfaces of the lugs and flanges will ride in contact with each other and the cap will be wedged into close contact with the outer face of the hub portion of the wheel.

In the inner face of the cap near the periphery thereof is formed an annular groove adapted to receive a gasket 1, of rubber, or like material, and the opposing face of the hub portion of the wheel is provided with a like annular groove, whereby when the cap is inserted and turned axially in the manner before stated, the gasket, 1, will be tightly pressed against the face of the hub to thereby make the joint between the cap and the hub absolutely air-tight. To hold these parts in an intimately locked condition and against any possibility of the cap turning backwardly to open the joint and destroy its air-tight character, one of the lugs on the cap is provided with a series of serrations or teeth, m, as shown in Fig. 4, or some similar

arrangement adapted to be engaged by a spring-pressed dog, *n*, as shown in Fig. 3, the said serrations or teeth serving as a ratchet and the dog serving as a pawl for engaging the same and holding the cap rigidly to the wheel, said cap having at its center a square or many-sided projection, *N*, adapted to receive a wrench or like tool whereby the cap may be turned reversely to unlock the cap and permit of its detachment from the wheel; the inner face of the cap is chambered so that it will act as a receiver for any oil which may escape outwardly past the journal.

Referring particularly to Fig. 5 it will be observed that the chamber surrounding the bushing and into which the oil is admitted, under pressure, is intersected by a passage, *O*, which is bored through the hub of the wheel and in this passage is mounted an appropriate spring-operated plunger, *P*, which is herein shown as comprising a suitable cup-leather packing, *p*, inclosed between two metallic or other washers, *R*, said washers and cup-leather being centrally pierced to receive a threaded rod, *S*, to the inner end of which is secured a nut, *T*, adapted to clamp the cup-leather securely between said washers.

The rod, *S*, extends outwardly through a bushing or threaded nut, *U*, mounted in the outer end of the passage and forming a closure therefor, and between this bushing or nut, and one of the washers, *R*, is confined a suitable coil spring, *W*. The rod is threaded at its outer end and this threaded portion extends through a corresponding hole in the bushing or nut, and beyond the same, the projecting portion being engaged by a nut, *V*, which is held to the rod by means of a cotter-pin, *4*, or like securing element. The tension of the spring may be adjusted at any time by the proper turning of the nut, *V*, upon the threaded rod, *S*, said nut serving, also, as an indicator of the condition of the oil in the oil chamber of the wheel, and normally standing about one-half inch above the outer surface of the bushing, *U*.

In practice, the oil under pressure is forced into the hub through the stop-cock, *I*, and the pressure in the oil chamber acts upon the spring-pressed piston to force the same outwardly against the tension of the spring, *W*, and at the same time moving the rod, *S*, and forcing the nut thereon outwardly until it stands about one-half inch beyond the outer face of the bushing, in which position the parts will remain until the pressure of the oil in the chamber, *A'*, is reduced, when the spring expands and the piston moves inwardly and thereby withdraws the rod and nut relatively to the fixed bushing, the nut in its position relatively to the outer side of the bushing indicating when more oil is

The oil under pressure completely surrounds the axle and is maintained around said axle by means of the cup-leather *G*, located at the inner end of the bushing and surrounding the journal portion of the axle, and by the chambered-cap which is hermetically locked over the outer end of the axle. Thus the oil is prevented from escaping in both directions and there is consequently no loss of oil and there is also an effective and automatic lubrication for the pressure in the oil chamber forces the oil through the perforations in the bushing and into contact with the journal end of the axle.

It is quite apparent that the spring-actuated piston may be omitted without departing from the spirit of my invention as the air under pressure when admitted to the chamber formed about the center of the wheel will compress the contained air in the upper portion of this chamber; after the supply of oil has been cut off and the valve closed, this trapped air will expand as the pressure of oil decreases, and consequently there will be an automatic force feed of the oil through the bushing to the journal as before described. The employment of the spring-actuated plunger will, however, facilitate the feed of the oil as the spring of the plunger will serve as an auxiliary means for applying pressure to the oil admitted to the chamber. My invention, therefore, comprehends the employment of compressed air and a spring or other mechanical means for maintaining a pressure on the oil and insuring the automatic feed to the journal end of the axle.

Having thus described my invention what I claim as new and desire to secure by Letters Patent is:—

1. The combination with an axle, of a wheel having a central opening and an enlarged lubricant-containing chamber surrounding the same, a bushing fitted to said opening having perforations connecting with said chamber, a valve-controlled pipe for conducting lubricant under pressure to said chamber, a cup-washer at one end of the bushing forming a tight-joint against the escape of oil along the axle in one direction and a cap detachably fitted to the outer side of the hub and forming an air-tight closure for the outer end of the bushing and axle.

2. The combination with an axle, of a wheel having a central opening, and an enlarged lubricant-containing chamber surrounding the same, a bushing fitted to said opening having perforations connecting with said chamber, a valve-controlled pipe for conducting lubricant under pressure to said chamber, a cup washer at one end of the bushing forming a tight joint against the escape of oil along the axle in one direction, and a cap detachably fitted to the outer side of the hub and forming an air-tight closure

for the outer end of the bushing and axle, said cap having lugs projecting from its periphery and said wheel having undercut flanges with open spaces therebetween and 5 adapted to interlock with the lugs on the cap when said cap is given a partial rotation, one of the said lugs of the cap having a ratchet surface and said wheel having a pawl to engage said surface to positively 10 lock the cap to the wheel.

3. The combination with an axle, of a wheel having a central opening, and an enlarged lubricant-containing chamber surrounding the same, said wheel having undercut flanges projecting from the outer face of its hub with open spaces between the flanges, a bushing fitted to said central opening having perforations connecting with said chamber, a valve-controlled pipe for conducting lubricant under pressure to said chamber, a washer at one end of the bushing, forming a tight joint against the escape of oil along the axle in one direction, a cap detachably fitted to the outer side of the hub 25 of the wheel and forming an air-tight closure for the outer end of the bushing and axle, said cap having lugs projecting from its periphery adapted to enter the spaces between the flanges on the wheel and to interlock with these flanges when the cap is given a partial rotation, one of the lugs of 30 said cap having teeth formed on it, and a spring-pressed member of the wheel adapted to engage said teeth to thereby positively 35 lock the cap to the wheel.

4. The combination with an axle, of a wheel having a central opening for the axle, and having a chamber surrounding the same and adapted to contain oil under pressure, a 40 bushing fitted to said opening having openings through it connecting with said chamber, a cup-washer surrounding the axle and abutting one end of the bushing, and a cap detachably fixed to the hub of the wheel and 45 forming substantially an air-tight closure over the outer end of the axle and bushing, said cap having a chambered inner face.

5. The combination with an axle, of a wheel mounted thereon, and having an internal chamber adapted to receive oil under 50 pressure, said chamber having an extension from one side, a piston slidably mounted in said extension and exposed to the pressure

of the oil therein, a bushing mounted in and forming a closure for the outer end of the extension, a spring between the bushing and piston and normally held under compression by the pressure of the oil and operating expansively to maintain a pressure on the oil as the supply of oil decreases and external 60 means for adjusting the tension of said spring.

6. The combination with an axle, of a wheel mounted thereon, a bushing fixed within the wheel and receiving the axle, a 65 cup-washer at the inner end of the bushing, a detachable air-tight closure over the outer end of the bushing and axle, a pipe connecting with said chamber adapted to deliver oil under pressure thereto, said chamber having 70 an extension at one side, a piston operating in said extension, and exposed to the oil pressure in the chamber and normally depressed under the action of said pressure, a spring backing the piston adapted to operate 75 to force the piston inwardly and maintain pressure on the oil as the supply of oil decreases, a rod connected with the piston and extending beyond the outer surface of the wheel, a bushing forming a closure for the 80 outer end of said extension, and a nut on the outer end of the rod for adjusting the tension of the spring, said nut serving in connection with an adjacent portion of the 85 wheel as a means for visually indicating the condition of the oil in the chamber.

7. The combination with an axle, of a wheel having a central opening and an enlarged lubricant-containing chamber surrounding the same, said opening adapted to 90 receive the journal end of the axle, a valve controlled pipe for conducting lubricant under pressure to said chamber, a cup washer confined in the hub of the wheel adapted to bear against the journal end of the axle to 95 form a tight joint against the escape of oil along the axle in one direction, and a cap detachably fitted to the outer side of the hub of the wheel and forming an air tight closure for the outer end of said axle. 100

In testimony whereof I affix my signature in presence of two witnesses.
